 Filed May 10, 1965, Ser. No. 454,531
 7 Claims. (Cl. 273—139)

ABSTRACT OF THE DISCLOSURE

A doodlebug fishing game simulating fishing a doodlebug from its vertical hole in the ground with a broomstraw. The game includes a base member having a top surface carrying a plurality of holes therethrough with a plurality of tubular members being concentric with the holes and depending therefrom. A pair of drawer-like members are slidably received in opposite ends of the base member and have recesses therein. Magnetically attractive game pieces are adapted to be carried in the recesses for withdrawal through the holes when the game is played by inserting a magnet-tip rod in the holes.

This invention relates to a doodlebug fishing game.

An object of the present invention is to provide a game simulating a game often played by young rural youths, that is, fishing a doodlebug from its vertical hole home-in-the-ground with a broomstraw.

A further object is to provide a game structure or game apparatus including a base member simulating the ground or the home of the doodlebug, a magnet-tipped shaft or rod simulating a broomstraw, and a plurality of magnetically attractive simulated doodlebugs; the general object in playing the game being to magnetically attract or retrieve the doodlebugs from the base member with the broomstraw.

A further object is to provide a game which is easy and simple to play and which does not require extensive rules or complicated procedures to be applied in playing the game.

A further object is to provide a game or an amusement structure which does not require liquids, heat, electricity, or the like and which is mechanically simple, strong and durable.

A further object is to provide a game structure which may be economically manufactured and marketed.

A further object is to provide a game requiring concentration upon the part of the players.

A further object is to provide a game having an element of chance involved in correctly guessing the hole in which a doodlebug is placed, and also an element of skill in retrieving the doodlebug from its hole without the doodlebug dropping from the broomstraw.

The means by which the foregoing and other objects of the present invention are accomplished and the manner of their accomplishment will be readily understood from the following specification upon reference to the accompanying drawings, in which:

FIG. 1 is a perspective view of the base member of the game apparatus of the present invention.

FIG. 2 is a top plan view of the base member in a partially disarranged disposition.

FIG. 3 is a sectional view illustrating a player fishing with a broomstraw for a doodlebug.

FIG. 4 is an enlarged fragmentarily illustrated showing of the broomstraw and the doodlebug.

In the drawings, the various parts are indicated by numerals. The base member, simulating the ground, is indicated by numeral 11; the simulated broomstraw is indicated by numeral 13; and each doodlebug of the plurality of doodlebugs is indicated by numeral 15.

Base member 11 includes a tubular open-ended sleeve

2

or body part 17 and a pair of drawer parts 19, 19' slidably fitted respectively in the oppositely disposed end portions of body part 17.

The game of the present invention is preferably designed to be played by two, four, or an even number of players. Base member 11 can thus be considered as being divided into two base sections or portions, as indicated by numerals 21, 21', with an opposing pair or opposing pairs of players being disposed oppositely or playing opposite each other. Base member 11 is symmetrically arranged on opposite sides of the imaginary line XY (FIG. 2). Since base sections 21, 21' are substantially alike, the following description of structure will be directed mainly towards base section 21, with corresponding parts of base section 21' being indicated by prime (') marks.

Base section 21 is provided with a plurality of holes 25 randomly spaced in top surface 27. Five holes are illustrated; it, of course, being understood that the number of holes 25 may be varied to suit the particular size of the game structure. Top surface 27 of base member 11 and the surfaces of base sections 21, 21' are preferably provided with simulated grass, as, for example, green paint, for a more realistic ground appearance.

Drawer 19 is fitted snugly in body part 17 with oppositely disposed side panels 29 engaging respective opposite side walls 31 of body part 17. Front panel 33 of drawer 19 is preferably provided with a knob 35. Five cup members 37 are fixedly secured on bottom panel 39 of drawer part 19. The arrangement of cup members 37 corresponds to the arrangement of holes 25 in the surface of top panel 41. The arrangement of holes 25 and cup members 37 is such that when drawer part 19 is slidably fitted in body part 17 and in a closed disposition, the plurality of cup members 37 are in vertical alignment with the plurality of holes 25. Five cylindrical tubular members 43 are preferably pendants attached to the undersurface of top panel 41. Tubular members 43 are adhesively attached respectively at the upper flanged portions 45 to the undersurface of top panel 41 at each of holes 25. The inside cylindrical surface of each of tubular members 43 is substantially the same size as a respective hole 25. Tubular members 43 serve to extend the depth of the associated holes 25. Tubular members 43 respectively project downwardly and terminate respectively in an annular lower edge 47. Cup members 37 respectively are in vertical alignment with tubular members 43, and the annular upper edges 49 respectively of cup members 37 are disposed concentric with and slightly below the respective lower edges 47 of tubular members 43. Each hole 25 opens upwardly in surface 27 of top panel 41 and opens downwardly over the recess 51 of a respective cup member 37. The inside cylindrical surface of each tubular member 43 and the interior of each cup member 37 is preferably painted black to hide the doodlebug.

Broomstraw 13 includes a long, thin rod or shaft 53 and a permanent-type magnet 55 secured on a tip end of the shaft. Magnet 55 is somewhat globular-shaped and is fixedly secured to the lower tip end of shaft 53. Shaft 53 is of plastic or non-metallic material. Also of non-metallic material are tubular members 43 and top panel 41 of base section 21.

Doodlebugs 15 are substantially alike, and each includes a head member 57 and a tail member 59. Head member 57 preferably includes a disc-shaped member 61 and is formed of magnetically attractive material or metal which is preferably black in color or is coated or painted black to prevent the players from seeing the doodlebugs. Tail member 59 is preferably formed of a series of beads 63 connected together and connected to disc member 61. A string 65, knotted on opposite ends and extending through apertures in beads 63 and disc member 61, pref-

erably fastens the respective parts of each doodlebug 15 together. Beads 3 and tail member 59 of each doodlebug and also cup members 37 are formed of plastic or other non-metallically attractable material. Each doodlebug 15 is preferably marked with a number or is painted a certain color to indicate a certain numerical value, and the plurality of doodlebugs are provided respectively with several marks or colors for indicating several different numerical values.

Various games may be played with the game apparatus of the present invention. In the several games that may be played, however, the general object of the game is for a player to guess where his opponent has placed the doodlebugs and to retrieve the respective doodlebugs from the holes and recesses without dropping the bugs from the broomstraw and back into the recesses. By way of exemplification, the following is a brief description of a game which may be played by two players with three paired bugs and with each pair of bugs being of unlike numerical value. Each player is given one bug of each pair of bugs, or three bugs. One player takes one side of base member 11 or base section 21, and the other player takes the other side of the base member or section 21'. Each player places the three bugs he has in cup member recesses 51, 51' of the respective drawers 19, 19' and slides the drawers into the respective base sections 21, 21'. After each player has placed the three doodlebugs in the recesses of the respective drawers, and the drawers closed, the players take alternate turns with broomstraw 13 in retrieving the doodlebugs that the other player has placed. Since only two players are playing the game, the player who first retrieves the three doodlebugs his opponent has placed in the recesses wins the game, or, if desired, the players may take a certain number of turns, as, for example, three turns, and after they have been taken, the player having the most doodlebugs wins the game. If four players or a larger even number of players play the game, an example of how the game can be played is to have that player who retrieves the number of doodlebugs totaling the highest numerical value win the game.

The present invention provides a game which is easy and simple to play and which does not require extensive rules or complicated procedures. The game structure does not require liquid, heat, electricity or the like and is mechanically simple, strong and durable. Concentration is required of the players in remembering or determining from which holes the doodlebugs have been retrieved. There is also an element of skill necessary in retrieving a bug from a recess and hole without the bug dropping from the broomstraw. In summary, the present invention provides a fascinating game affording many hours of pleasure for the players.

Although the invention has been described and illustrated with respect to a preferred embodiment thereof, it is to be understood that it is not to be so limited since changes and modifications may be made therein which are within the full intended scope of this invention as hereinafter claimed.

I claim:

1. A doodlebug fishing game comprising, in combination, a base member simulating the ground, said base member being elongated and including a first base section and a second base section, each said base section including a body part having a top surface and a drawer part movably secured to said body part, means providing in said body part a plurality of vertically extending elongated holes with each hole having an upper end opening upwardly in said top surface and a lower end opening downwardly into the interior of said body part, means providing in said drawer part a plurality of upwardly opening recesses corresponding in number to said plurality of holes, said body part and said drawer part of each said base section being arranged with each said recess being disposed directly underneath the downwardly opening lower end of a respective hole of said plurality of holes, each

said base section having a number of holes and recesses equal in number to the number of holes and recesses of the other of said base sections; a plurality of simulated doodlebug game piece means randomly placed in at least some of said recesses, simulated straw retrieving means for insertion in a selected one of said holes and for movement adjacent one of said recesses corresponding to said selected one of said holes, and magnetic means on said simulated straw means for magnetically attracting one of said doodlebug means when in said one of said recesses whereby said one of said doodlebug means can be withdrawn by said straw means.

2. A doodlebug fishing game comprising, in combination, a base member simulating the ground, a simulated broomstraw retrieving means, and a plurality of simulated doodlebug game piece means; said base member being divided into a plurality of base sections having a top surface, means extending downwardly and providing in said base sections a plurality of vertically elongated holes with each hole having an upper end opening upwardly in said top surface and a lower end opening downwardly into the interior of said base sections at a place spaced substantially downwardly from said top surface, means providing in said base sections a plurality of upwardly opening recesses corresponding in number to said plurality of holes and respectively disposed therebeneath; said simulated broomstraw including a long, thin shaft and a substantially small permanent-type magnet secured on the tip end of said shaft; each doodlebug of said plurality of simulated doodlebug game pieces including a head member of magnetically attractable material and each doodlebug being adapted to be carried in one of said recesses; the game being adapted to be played by an even number of players who conceal a like plurality of doodlebugs respectively in each said base section and in the respective recesses of each of said base section, an object in playing said game being to correctly guess the hole each doodlebug is in and to magnetically retrieve the doodlebug from the recess and through the hole with the broomstraw.

3. A doodlebug fishing game comprising a base member simulating the ground, a simulated broomstraw retrieving means, and a plurality of simulated doodlebug game piece means; said base member being divided into a plurality of base sections with each base section including a body part having a top surface and a drawer part movably secured in said body part, means providing in said body part a plurality of vertically extending elongated holes with each hole having an upper end opening upwardly in said top surface and a lower end opening downwardly into the interior of said body part, means providing in said drawer part a plurality of upwardly opening recesses corresponding in number to said plurality of holes, said body part and said drawer part of each said base section being arranged with each said recess being disposed directly underneath the downwardly opening lower end of a respective hole of said plurality of holes, each said base section having a number of holes and recesses equal in number to the number of holes and recesses of each other base section; said simulated broomstraw including a long, thin shaft and a substantially small permanent-type magnet secured on a tip end of said shaft; each doodlebug of said plurality of simulated doodlebug game pieces including a head member of magnetically attractable material and a tail member of non-magnetically attractable material; the game being adapted to be played by a number of players who each conceal a like plurality of doodlebugs respectively in each said base section and in the respective recesses of each said drawer part, an object in playing said game being to correctly guess the hole each doodlebug is in and to magnetically retrieve the doodlebug from the hole with the broomstraw.

4. The game of claim 3 in which each said simulated doodlebug includes indicia means on said doodlebug for indicating a numerical value, and in which said plurality of simulated doodlebugs are provided respectively with several dif-

ferent indicia for indicating several different numerical values; an object of the game being for a player to catch or magnetically retrieve the number of doodlebugs totaling the highest numerical value.

5. A doodlebug fishing game comprising a base member simulating the ground, a simulated broomstraw retrieving means, and a plurality of simulated doodlebug game piece means; said base member being elongated and including a first base section and a second base section opposingly arranged longitudinally of said base member, each said base section including a body part having a top surface and a drawer part movably secured in said body part, means providing in said body part a plurality of vertically extending elongated holes with each hole having an upper end opening upwardly in said top surface and a lower end opening downwardly into the interior of said body part, means providing in said drawer part a plurality of upwardly opening recesses corresponding in number to said plurality of holes, said body part and said drawer part of each said base section being arranged with each recess of said plurality of recesses being disposed directly underneath the downwardly opening lower end of a respective hole of said plurality of holes, each said base section having a number of holes and recesses equal in number to the number of holes and recesses of the other of said base sections; said simulated broomstraw including a long thin shaft and a substantially small permanent-type magnet secured on a tip end of said shaft; each doodlebug of said plurality of simulated doodlebugs including a head member of magnetically attractable material and a tail member of nonmagnetically attractable material, said tail member being formed of a series of beads connected together and extending outwardly from said head member, each said doodlebug of said plurality of doodlebugs including a mark or color fixed to said doodlebug for indicating a numerical value, said plurality of doodlebugs also being provided respectively with several different marks or colors indicating several different numerical values for individual doodlebugs; the game being adapted

to be played by a number of players who each conceal like pluralities of doodlebugs respectively in each said base section and in the respective recesses of each said drawer part, an object in playing the game being to correctly guess or to know the hole in which a doodlebug is placed and to magnetically retrieve the doodlebug from the hole with the broomstraw; a further object in playing the game being for a player to catch or magnetically retrieve the number of doodlebugs totaling the highest numerical value as indicated respectively by the markings or colors of the respective doodlebugs.

5 10 15 20 25 30 35

6. A game comprising a base member having a top surface carrying a plurality of holes therethrough, tubular members concentric with said holes and depending therefrom, means providing recesses, said recesses being disposed beneath and in alignment with said tubular members and holes, said tubular members having lower ends disposed adjacent said recesses, magnetically attractable game piece means adapted to be carried in said recesses, and means including a magnet for withdrawing said game piece means from said recesses through said holes.

7. The game of claim 6 in which said tubular members are secured to the underside of said top surface in registry with said holes, and in which said means providing said recesses includes a second member received in said base member and having said recesses therein.
